UNITED STATES PATENT OFFICE.

SAMUEL SEABURY, OF BERGEN POINT, NEW JERSEY.

BREECH-LOADING ORDNANCE.

SPECIFICATION forming part of Letters Patent No. 448,269, dated March 17, 1891.

Application filed March 16, 1889. Serial No. 303,598. (No model.)

To all whom it may concern:

Be it known that I, SAMUEL SEABURY, lieutenant United States Navy, residing at Bergen Point, in the county of Hudson and State of New Jersey, have invented a new and useful Improvement in Breech-Loading Cannon, of which the following is a specification, reference being had to the accompanying drawings. This invention relates to breech-loading

5 cannon in which a screw breech-block is employed in a swinging carrier hinged to one side of the breech of the gun.

The invention consists in the combinations hereinafter described and claimed, whereby 15 such a breech-block is automatically unlocked, withdrawn, and moved laterally away from the breech of the gun and held away from the breech-opening for loading, and whereby after the loading the said block is automatically 20 returned to the breech-opening, inserted therein, and locked in position for firing.

The invention further consists in certain 25 mechanism, hereinafter described and claimed, whereby the recoil movement of the gun is caused to produce, first, the unscrewing movement of the breech-block in the breech of the gun, and afterward the backward and outward movement of the carrier and breech-block to open the breech, and the forward 30 movement of the gun to the firing-position is caused to produce, first, the inward and forward movement of the carrier and the breech-block, and afterward the screwing up of the breech-block.

35 The invention also consists in certain improvements, hereinafter described and claimed, in the lock of a breech-loading cannon of the kind hereinbefore mentioned, whereby the cocking may be effected either 40 by the act of opening the breech or by hand, and safety against accidental firing is assured.

Figure 1 is a side view of the rear portion 45 of its carriage, illustrating my invention. Fig. 2 is a rear view of the same. Fig. 3 is a front view of the breech-block. Fig. 4 is a plan view of the breech of the gun with the breech-block and carrier in an open position. Fig. 5 is a horizontal sectional view, on a larger

scale than the preceding figures, of the breech portion of the cannon, the breech-block and its carrier, and the lock. Fig. 6 is a perspective view of the trigger. Fig. 7 represents one of the details of the breech-operating mechanism, which will be hereinafter fully described. Fig. 8 represents a horizontal section of the breech-block and part of its carrier and a plan of the firing mechanism, partly in section, on a larger scale than Fig. 6, showing the firing-pin cocked. Fig. 9 is a rear view corresponding with Fig. 8. In the two last-mentioned figures all parts not necessary to illustrate the firing mechanism are omitted.

65 Similar letters and figures of reference designate corresponding parts in all the figures.

C C' designate the lower or training member of a gun-carriage, consisting of a cylinder C, intended to turn upon a pivot (not shown in the drawings), and a table C', which constitutes the head of said cylinder, and upon which are constructed parallel ways g for the support of the upper member E of the carriage, which contains the bearings for the 70 trunnions of the gun V, the said upper member E being capable of running to and fro on the said ways to permit the recoil of the gun and its forward movement to the firing position. The ways g are represented as constructed on two horizontal hydraulic cylinders D, which are firmly secured upon the table C', and which contain pistons which are connected by rods G' with the upper member E of the carriage for the purpose of producing 75 the necessary resistance to the recoil of the gun. This construction of the carriage constitutes no part of the present invention; but it serves as well as any other construction to illustrate my invention, which is applicable with all kinds of gun-carriages in which an upper member or carriage runs back and forth upon a lower member or carriage.

N P designates the breech-block carrier 93 consisting of a frame N, which is attached by an upright hinge u u' to one side of the gun close to the breech thereof, and a stem P, firmly secured to the said frame. The stem P has at its front end a nose-plate 20, and it 100

is secured in the frame N by a screw-thread on its rear portion and a nut 21, which clamps it to the said frame. The relation between the breech-carrier and the bore of the gun is such that the stem P may occupy a position concentric with the bore of the gun, as shown in Fig. 5.

Q designates the breech-block, which is screw-threaded externally to fit into an internally-screw-threaded seat provided for it in the rear of the bore of the gun. In the example represented the screw-threads 22 23 of the breech-block and the corresponding threads of the interior of the seat in the gun consist of two sets of different diameters, and the said screw-threads 22 23 and corresponding screw-threads in the seat are mutilated at alternate intervals to allow the breech-block to pass into the seat without turning and to allow the breech-block to be screwed tight into the seat by a comparatively small movement on its axis, say, one-sixth of a revolution.

The construction of the carrier and breech-block so far described is old and well known; but I have found its description necessary to a proper explanation of my improved mechanism for operating them, which I will now proceed to describe in detail.

The pivot of the hinge u u' , upon which the breech-block carrier swings, consists of an upright pin or spindle u^2 , which passes through the portions u of the hinge which are formed on the carrier and the portion u' of the hinge which is secured by screws u^3 to the gun in such manner as to be capable of turning in all of them to some extent, and it is furnished below the hinge with an arm u^4 and below the said arm with a spur-gear u^5 , the said spur-gear gearing with a horizontal rack v , to be presently described, for the purpose of producing the turning movement of the said pin, by which both the swinging movement of the carrier and the turning movement of the breech-block upon its axis are produced. The arm u^4 is connected by a rod u^6 with a swivel u^7 , which is pivoted to an arm u^8 , which is secured by screws u^9 to the back of the breech-block.

In order to provide for producing the swinging movement of the carrier by the turning of the spindle u^2 , but to permit a certain amount of movement to the said spindle and the attached arm u^4 without producing any movement of the carrier, a key is provided on the said spindle, the said key consisting in the example shown of a short pin or projection u^{10} , provided on the arm u^4 and projecting upward from the said arm into a recess u^{12} (see Figs. 1 and 2) in the bottom of the lower part u of the hinge, which is constructed on the carrier. The pin or projection u^{10} turns with the spindle u^2 with a certain amount of lost motion in the recess u^{12} , so that it may produce the opening movement of the carrier by pressing against the forward end of the said recess, but that a certain

amount of movement may be permitted to the arm u^4 for turning the breech-block in the carrier without moving the carrier.

The toothed rack v , hereinbefore mentioned, with which the spur-gear u^5 gears, is provided in one side of a slotted head on the rear end of a bar v' , which works through a guide v^2 , secured on the outside of the gun and through a friction-sleeve w , which is provided on a slide w' , which is fitted to work up and down freely on an arc-shaped standard w^2 , which is firmly secured to the table C' of the lower carriage, the arc of the said standard being concentric with the trunnions of the gun when the gun is run forward to the firing position. In the rear of the slide w' a tappet-collar w^3 is secured to the rack-bar v' by a set-screw. The bar v' , besides being guided in the guide v^2 , is guided by the slot v^3 in its head, (see Fig. 5,) running on the spindle u^2 , which passes through the said slot and the rack, and is further kept in place by the portion v^4 of the head on each side of its slot running on the top face of the gear u^5 .

In order to insure the retention of the breech-block in the carrier in a proper position to re-enter the seat in the breech, I provide a locking device which locks the breech-block to the carrier in such manner as to prevent it from turning, except at the proper time. This locking device in the example represented consists of a key 24, formed on the end of a hammer-like piece 25, (see Figs. 2, 4, and 5,) which is pivoted by a pin 26 within a slot in the carrier. This hammer-like piece is constructed with a toe 27, which projects through the front of the carrier, as shown in Fig. 5, to enter a curved recess 28, provided in one side of the breech-seat in the gun. This toe is pressed upon by a spring 29, secured within the carrier in such manner as to tend to force the point of the key 24 forward beyond the inner face of the carrier and against the outer face of the breech-block. In this outer face there is provided a notch 30, (shown fully in Fig. 2 and dotted in Fig. 5,) which is so situated that when the breech-block is turned to the position in which it is unlocked from the breech-seat the key 24 will enter the said notch and so lock the breech-block and the carrier together, as shown in Fig. 4, where the key is represented in dotted outline as entering the notch. During the act of moving the breech-block forward into the seat the toe 27 moves along the camway constituted by the curved face of the recess 28 in the seat to the position shown in Fig. 5, and so withdraws the key 24 and leaves the breech-block free to turn in the seat for the purpose of locking it. The turning movement of the breech-block in the opposite direction for the purpose of unlocking it brings the notch 30 again opposite to the key 24, and as the carrier and the breech-block swing back together the toe 27 of the key is released from the breech-seat and the spring 29, acting on the said toe, throws the key 24 forward

into the notch, and so causes the breech-block and the carrier to be locked together and to remain locked until the breech-block is again swung into its seat. The key 24 is provided with a thumb-piece 31, resembling the comb of a gun-hammer, for the purpose of enabling the unlocking of the breech-block from the carrier to be performed by hand if in any case it may be necessary.

10 The swinging movement of the carrier to carry the breech-block to and from the breech of the gun and the turning movement of the breech-block in the carrier to screw it up and unscrew it are produced by the movement of the gun in the following manner: I will first suppose the gun to be in the position for firing, (shown in Fig. 1,) the upper carriage E being in its forward position upon the lower carriage C C'. The breech is now closed and 15 screwed up, as shown in Figs. 1, 2, and 5, and the tappet-collar w^3 on the rack-bar v' is stopped against the slide w on the standard w^2 . The gun having been fired and its recoil taking place, the spur-gear u^5 , moving back 20 with the gun, tends to carry with it the rack v , but this tendency is restrained by the friction of the sleeve w , through which the rack-bar v' passes, and the gear in running backward along the rack is caused to turn on its own 25 axis and to cause the spindle u^2 to turn with it and so carry the arm u^4 in an outward direction and cause the said arms, by means of the rod u^6 , the swivel u^7 , and the lever-arm u^8 , to turn the breech-block in the direction of the 30 arrow shown upon it in Fig. 2, and so unscrew it far enough to bring its threads opposite the mutilations of the threads of the breech-seat in the gun, and thus permit the breech-block to be withdrawn from the seat.

35 When the breech-block has been thus far turned, the pin or projection u^{10} of the arm u^4 strikes the forward end of the recess u^{12} in the lower portion u of the hinge of the carrier. As the pinion and the arm u^4 continue 40 to turn the key or projection u^{10} , pressing against the said end of the recess u^{12} , causes the carrier and the breech-block to swing outward to open the breech, the carrier and the breech-block being then locked together in 45 the manner hereinbefore described by the key 24. After the loading of the gun and as it is run forward the spur-gear u^5 , the rack v , and the rack-bar v' are at first held stationary by the friction of the sleeve w on 50 the rack-bar, and the spur-gear running forward along the rack causes the spindle u^2 to be turned, and the arm u^4 moving with it and acting through the rod u^6 , the swivel u^7 , and the arm u^8 on the breech-block causes the 55 breech-block and the carrier to move together toward the closing position, bringing the breech-block into its seat with its threads opposite the mutilations of the threads of the seat. The movement of the carrier is thus 60 stopped, and during the continued forward movement of the gun the sleeve w slides along the rack-bar. If the breech should

fail to have its movement completed through the friction of the sleeve, the tappet-collar w^3 , coming in contact with the sleeve w , will 70 cause a positive stoppage of the rack-bar and rack and the complete closing of the breech. The breech-block now having been unlocked from the carrier by the action of the toe-piece 27, hereinbefore described, during the continued forward movement of the gun, the spur-gear continues to be turned by running in the rack, and thus the key or projection u^{10} moves within the recess u^{12} in the hinge of the carrier, and the continued movement of the arm u^4 , with the spindle u^2 acting through the rod u^6 , the swivel u^7 , and the lever-arm u^8 on the breech-block, turns the breech-block in an opposite direction to the arrow shown in Fig. 2 and screws up the 85 breech. In the upward and downward movement of the gun for giving it a proper elevation the slide w' moves up and down freely on the standard w^2 , and therefore no tendency is produced to move the slide w' upon 90 the rack-bar v' or to move the said bar lengthwise by this movement of the gun.

I will here explain with reference to Fig. 7, which represents a transverse section of the rack-bar and a back view of the slide and friction-sleeve, that the friction between the sleeve and the rack-bar is produced by means of a set-screw w^4 , screwed into the sleeve and pressing against a friction-saddle w^5 , fitted to the bar within the sleeve.

I will now describe the lock. R designates the firing-pin, consisting, as shown in Figs. 5 and 9, of two straight portions united by a loop at the rear and forming a fork with two straight prongs. The longer straight portion 105 or prong passes through the stem P, which is counterbored to receive the coiled mainspring 32, which is compressed between a collar 33 on the pin and a nut 34, which caps the outer end of the stem. The collar 33 fits 110 the counter-bore in such a manner as to slide freely therein and serve as a guide for the longer prong of the firing-pin, which passes through said collar and counter-bore. Between the collar 33 and the shoulder of the 115 counter-bore there is a spring 35, consisting of a concavo-convex disk, (see Figs. 5 and 9,) the purpose of which is to withdraw the point of the pin within the nose-plate 20 after it has been relieved from the momentum given 120 to it by the sudden expansion of the mainspring. The shorter prong of the firing-pin passes outside of the stem P between two lugs 42, (see Figs. 4, 5, 8, and 9,) provided on the outside of the carrier N, which prevents 125 it from turning. The said shorter prong has in its end a notch 36 for the engagement of the stirrup-like sear 38 of the trigger T, (see Figs. 5 and 6,) and has on its outer side a lateral projection 37 to be acted upon by a wedge 130 like cam 39 (see Figs. 1, 8, and 9) on the rear of the breech-block for the purpose of cocking the pin by the turning movement of the breech-block, by which it is unlocked from

its seat. The wedge-like nature of this cam is best shown in Fig. 1. As it is curved, as shown in Fig. 2, and concentric with the breech-block, its face has the character of the face of a screw-thread. The trigger T, which is shown in perspective in Fig. 6, is composed of a stirrup-like portion, the cross-bar 38 of which constitutes the sear, an upright stem 40, projecting above and below the stirrup-like portion, and a horizontal arm 41, projecting from the bottom of the stem 40 at right angles to the stirrup-like portion 38. The stirrup-like portion embraces the two lugs 42, (see Figs. 4 and 5,) which are formed on one side of the breech-block carrier, and two pins 43, passing one through the upper and the other through the lower portion of the stem 40 and screwed into the lugs 42, serve as the pivots upon which the said trigger works. The arm 41 has an eye for the attachment of a lanyard for firing. The other straight portion of the firing-pin passes through the stirrup of the trigger, and the latter is supported above and below the firing-pin very firmly. The sear-spring 44 for the trigger, by which the cocking is effected after the drawing back of the firing-pin, as shown in Fig. 5, is secured to one side of the inner hub of the carrier. It has been hereinbefore explained how the firing-pin is cocked by the cam as the breech-block is turned for the purpose of unlocking it from its seat. If desired, the cocking can be effected by hand by taking hold of the loop at the rear of the pin, which is constructed to always protrude from the rear of the carrier for that purpose. The cam 39, besides serving the purpose of cocking the firing-pin, also serves as a safeguard to prevent the firing-pin from striking the primer of the cartridge until the breech-block is turned to the position to completely lock it, for the pin cannot strike the cartridge while any but the lowest portion of the cam 39 is opposite the projection 37, and the lowest portion of the cam cannot be opposite the projection 37 until the breech-block is fully locked.

In order to provide for producing the movements of the swinging breech-block carrier on its hinge and the turning movement of the breech-block in said carrier by hand, there is represented in Fig. 1 on the lower part of the hinge-pin u^2 a square adapted to receive a handle, by which the said pin may be turned in the same manner in which it is turned by the action of its spur-gear u^5 and the rack r . When it is to be thus turned, it will be desirable to loosen the friction-sleeve w by unscrewing the screw w^4 , so that the rack-bar w^3 may move freely. Otherwise it would be necessary to provide for throwing either the gear or rack out of gear.

What I claim as my invention, and desire to secure by Letters Patent, is—

1. The combination of the gun, the breech-block, means for locking it in the breech of the gun, means for automatically rotating the

breech-block to unlock and withdraw it from the breech of the gun, means for moving the breech-block laterally away from the breech-opening, and devices for then holding the breech-block away from the breech-opening, substantially as herein described. 70

2. The combination of the gun, the breech-block, means for locking it in the breech of the gun, means for automatically rotating the breech-block to unlock and withdraw it from the breech of the gun, means for moving the breech-block laterally away from the breech-opening, a stop for then holding the breech-block away from the breech-opening, and mechanism for automatically returning the breech-block to the breech-opening, inserting it therein, and locking it in position when the stop is released, substantially as herein described. 75 80 85

3. The combination, with the gun-carriage and a breech-loading gun thereon, of a hinged swinging breech-block carrier, a gear attached to the hinge of said carrier and concentric therewith, and a rack attached to a portion of the gun-carriage which does not move with the recoil of the gun and engaging with said gear for the purpose of producing the swinging movement of said carrier and the breech-block for opening and closing the breech by the backward and forward movement of the gun, substantially as and for the purpose herein specified. 90 95

4. The combination, with a gun-carriage and a breech-loading gun thereon having a hinged swinging breech-block carrier, of a spindle passing pivotally through the hinge of the carrier and a key on said spindle engaging with the said carrier, a gear on the said spindle, and a rack attached to a portion of the carriage which does not move with the recoil of the gun and engaging with said gear for the purpose of producing the swinging movement of the carrier and breech-block for opening and closing the breech by the backward and forward movement of the gun, substantially as and for the purpose herein specified. 100 105 110

5. The combination, with a gun-carriage and a breech-loading gun thereon having a hinged swinging breech-block carrier and a screw breech-block fitted to turn in said carrier, of a spindle passing pivotally through the hinge of the carrier and bearing a gear rigidly attached to said spindle, an arm on said spindle, a rod connecting said arm with the breech-block, a key on said spindle engaging the carrier with a lost motion, and a rack attached to a portion of the gun-carriage which does not move with the recoil of the gun and engaging with said gear for the purpose of producing both the swinging movement of the carrier and the turning movement of the breech-block in the carrier by the backward and forward movement of the gun, substantially as and for the purpose herein specified. 115 120 125 130

6. The combination, with a breech-loading

- gun having a hinged swinging breech-block carrier, and a carriage for said gun, consisting of a lower training carriage or member and an upper carriage or member on which the gun is directly mounted by its trunnions, and which is capable of moving back and forth on the lower carriage or member in a direction lengthwise of the gun, of a gear attached to said carrier, a rack engaging with said gear, 5 a rack-bar connecting said rack with said lower carriage, an arc-formed standard secured to the said lower carriage or member in a position concentric with the trunnions of the gun in one position of the latter, and a slide connected with said rack-bar and fitted to slide up and down on said standard, substantially as and for the purpose herein set forth.
7. The combination, with a breech-loading gun having a hinged swinging breech-block carrier, and a carriage for said gun, consisting of a lower training-carriage and an upper longitudinally-moving carriage, of a gear attached to the hinge of said carrier and concentric therewith, a rack gearing with said gear, a bar carrying said rack, and a frictional sleeve fitted to said bar and attached to the lower carriage to serve as a sliding connection between said rack and the lower carriage, substantially as herein set forth.
8. The combination, with a breech-loading gun, of a swinging breech-block carrier, a mutilated-screw breech-block fitted to turn therein, a spring-actuated locking-key for locking
- the said breech-block against turning in the carrier while out of the gun, and a camway in the breech-seat, in contact with which the said key moves to withdraw the said key from the breech-block to allow the latter to be turned to lock it in the gun, substantially as herein set forth.
9. The combination, in a breech-loading cannon, with a hinged swinging breech-block carrier having a central stem and a mutilated-screw breech-block turning on said stem, of a firing-pin composed of two straight portions, one passing through said stem and the other passing outside of said stem and provided with a projection, a trigger pivoted to said stem and engaging with the outside portion 50 of said pin, and a cam on the said breech-block for operating on the said projection for cocking the pin, substantially as herein set forth.
10. The combination, with the stem of the swinging breech-block carrier, of a forked firing-pin, the firing-prong of which passes through and the other prong of which passes outside of said stem, a mainspring for said firing-pin, and a trigger having a stirrup-like portion through which the last-mentioned prong of the firing-pin passes, and which constitutes the sear, substantially as herein described.

SAMUEL SEABURY.
